APPARATUS FOR CONTROLLING THE FLOW
OF DYE LIQUOR THROUGH KIERS

William E. J. McMann, Danville, Va.

Application January 16, 1948, Serial No. 2,671

9 Claims. (Cl. 68—189)

1

This application relates generally to dyeing, and particularly to the regulation of beam dyeing processes, so as to eliminate the necessity for constant attention by an operator, and the causes of blown beams, crushed beams, and non-uniform dyeing.

In the dyeing of yarn on a large scale, it is the usual practice to wind as much as 17,000 yards of yarn on a so-called "beam." The beam is a relatively large reel, having a reticulated core which is adapted to be received within a kier, and separate the kier into two pressure chambers, with the yarn wound on the reticulated core constituting the previous wall between the chambers. Dye liquor is circulated through the kier, first in one direction (as from outside the yarn on the beam toward the interior), then in the other direction (as from inside the beam outwardly through the yarn), for a time sufficient to accomplish the desired shade. In such an operation there exists a pressure differential between that side of the yarn on the beam through which the dye liquor enters, and that side of the yarn on the beam through which the dye liquor leaves. The differential is periodically reversed by the manipulation of a four-way valve conventionally employed for the purpose. The reversals of circulation have hitherto been accomplished automatically, by an apparatus known in the art as a cycle cam.

As an incident to the reversal of the direction of flow, the pressure differential within the kier is subject to sudden changes and surges. This frequently results in disturbing the relation of the yarn on the beam, to the extent that a limited path of lesser resistance to flow of the dye liquor than the body of yarn, is created. Since the dye liquor under pressure seeks the path of least resistance, more liquor will flow through one section of yarn than through another, with consequent non-uniformity of shade. In some cases the beam of yarn is thereby ruined; in other cases, the beam may be rewound on another beam and re-dyed. In either event, the damage is expensive. These difficulties are known in the art as "blown beams." Another difficulty which the art has experienced as an incident to sudden surges of pressure in the kier results in the mechanical failure of the reticulated core of the beam. This is known in the art as "crushed beams;" and damages not only the beam itself, but the yarn thereon.

In the dyeing industry, loss of time, equipment, and material resulting from crushed beams and blown beams amounts to many thousands of

2

dollars annually. The constant likelihood of such damage requires that an operator give constant attention to the pressures within the kier, and be ready at any instant to interrupt the operation.

The object of the present invention, generally stated, is to automatically regulate beam dyeing operations so as to eliminate the necessity of constant attention by an operator, and minimize the likelihood of loss due to crushed and blown beams.

Other objects will be apparent to those skilled in the art as the following description is read in connection with the accompanying drawing, 15 wherein the single figure is a diagrammatic view of a beam-dyeing system provided with automatic regulation apparatus in accordance with the present invention.

The present invention contemplates the automatic control of yarn drying process, and makes use of the conventional kiers, beams, pumps, valves, and cycling mechanism.

The single figure of the drawing is a diagram showing the correlation of the conventional kier, 25 pump, four-way valve, and the interconnecting pipes in correlation with the control devices of the present invention.

In order to orient the invention, the conventional parts of the system as shown in the accompanying drawing will first be pointed out. A kier 1 having a beam 2, on which the yarn to be dyed is wound, is connected to an unidirectional pump 3. The pump 3 is driven by a motor 4. Pipes 5 and 6 extend respectively from the intake and output ports of the pump. A power-driven four-way valve 7 (shown in section) is arranged to connect pipes 5 and 6 selectively to pipes 8 and 9, the former extending from the valve 7 to a beam surface port 80 and the latter extending from the valve 7 to a beam axis port 90 in the kier 1. The valve 7, when in the position shown in full lines, connects pipe 5 with pipe 9, and pipe 6 with pipe 8, thus inducing flow of the dye liquor in the direction indicated by the full arrows (the exterior of the beam being at higher pressure than the interior). To reverse the flow of dye liquor (as indicated by the broken arrows), the valve 7 is moved to the position shown in dotted lines, wherein pipe 5 is connected with pipe 8, and pipe 6 with pipe 9. To move valve 7 between the two positions, there is provided an air cylinder 10, having a piston 11 whose rod terminates in a rack 12, inter-engaging with a pinion 13 on the valve. The cylinder 10 is energized by compressed air from source 14, controlled

by a slide valve 15 which, in the position shown, admits the compressed air through pipe 16 behind piston 11. In the opposite position of slide valve 15 (toward which it is loaded to move automatically), connection is made with pipe 17 which communicates with the interior of cylinder 10 ahead of piston 11, so that valve 7 is activated to its dotted line position. Valve 7 is periodically moved between its two positions by a timing mechanism commonly called a "cycle cam," and indicated generally at 18. The cycle cam is a chronometer, arranged to control the flow of compressed air from a supply 19, through a pipe 20, to an actuating cylinder 200 for a slide valve 15. For a predetermined period of time (while air is admitted from supply 19 to pipe 20), the slide valve 15, piston 11, and valve 7 will be in the positions shown. Then for a predetermined period, the flow of air from pipe 19 to pipe 29 is interrupted, with the result that the slide valve 15, piston 11 and valve 7 assume their opposite positions (wherein pipe 5 is connected with pipe 8). The cycle cam also controls motor 4 so that on each occasion while valve 7 is being moved between its two positions, the supply of electric power to motor 4 is interrupted, and when valve 7 has been re-positioned the motor is restarted. In addition to the aforementioned apparatus, the conventional dyeing system included a pressure gauge involving a diaphragm 21 located within the kier, and an indicator which was generally of the recording type.

In accordance with the present invention, a variable constriction valve is applied to the discharge outlet of pump 3, and the degree of opening of said valve is automatically varied to maintain the pressure on diaphragm 21 within one set of predetermined limits when the flow of dye liquor is in one direction, and within another set of predetermined limits when the flow of dye liquor is in the opposite direction. A further feature of the invention resides in the arrangement of the control apparatus, so that the constriction valve is operated toward closed position when the flow of power to the pump motor is interrupted.

The variable constriction valve is shown at 22. The area of the orifice through valve 22 is controlled by turning stem 23, which latter is geared to a reversible electric motor 24. Operation of motor 24 is controlled by magnetic switches 25 and 26, and which are controlled respectively by electro-pneumatic relays 27 and 28. Relay 27 is constructed to close its circuit when the pneumatic pressure thereon is at a high value, as for example 9 pounds or more per square inch. Relay 28 is constructed to close its circuit when the pneumatic pressure thereon is at a low value, as for example 6 pounds or less per square inch. Between the operating values of the two relays, a substantial pressure range exists in which neither relay closes its circuit. The circuits are arranged so that when relay 27 closes its circuit, motor 24 is operated in the direction to increase the area of the orifice through valve 22; and conversely when relay 28 closes its circuit, the motor 24 reduces the area of the orifice through valve 22.

Relays 27 and 28 are actuated by air from line 29. The pressure in line 29 is variable, and at any increment of time depends not only upon the pressure on diaphragm 21, but also upon the direction of dye liquor flow, and also upon whether or not motor 4 is energized. The air in line 29 is supplied from a line 30 at substantially constant pressure, and is controlled in the first instance by

an electro-magnetic valve 31 which is open when motor 4 is energized, but closed when the power supply to motor 4 is interrupted. From valve 31 the air passes through tube 32 to a pressure recording controlling instrument 33, which has an index pointer 34 (the position of which is determined by the direction of flow of the dye liquor), and an indicating pointer 35 (the position of which reflects the actual pressure on diaphragm 21 within the kier). Index pointer 34 is in the position shown in full lines when the flow of dye liquor is in the direction of the full arrows, and in the position shown in broken lines when the flow of dye liquor is in the direction of the broken arrows. The instrument 33 also contains an air pressure reducing valve 36, of any well known type wherein a part 50 may be moved to vary the output pressure to any value below the input pressure. The position of valve 36 (and hence the output air pressure thereof) is dependent upon the relative positions of pointers 34 and 35, irrespective of whether pointer 34 is in its high position (shown in full lines), or its low position (shown in broken lines). The instrument 33 may be of any known type wherein input compressed air is reduced and delivered at pressure above or below a median, depending upon whether one indicated quantity (such as pointer 35) is above or below another indicated quantity (such as pointer 34), provided the latter indication is automatically adjustable. Such instruments are obtainable upon the market in forms which involve intricate mechanism for assurance of accuracy, sensitivity of action, and anti-hunting. Complete understanding of the details of such an instrument is unnecessary for disclosure of the present invention, and consequently the accompanying drawing is not encumbered with them. In the form of instrument diagrammatically shown in the drawings, the pointer 34 is mounted upon a shaft 51, to which is secured a gear 52, and the pointer 35 is mounted upon a shaft 53, upon which is secured a gear 54. The gear 54 is meshed with an idling gear 55, which in turn meshes with a gear 57 at one end of a differential mechanism 56. The gear 52 meshes with a gear of the same size as gear 51, but at the other end of the differential mechanism. Part 50 of valve 36 is connected to the differential mechanism 56 through a rack 58 and a pinion 59 so that when the two pointers 34 and 35 are substantially aligned, the air output from valve 36 is at median pressure (e. g. between 6 and 9 p. s. i.), when pointer 35 is above pointer 34 the air output of valve 36 is below the median pressure, and when pointer 35 is below pointer 34 the air output of valve 36 is above the median pressure.

The output side of pressure reducing valve 36 is connected to air line 29, which as above indicated, supplies the energy for actuating relays 27 and 28.

To move the index pointer 34 between the position shown in full lines (when the direction of dye liquor flow is as indicated by the full arrows), and the position shown in dotted lines (wherein the direction of flow of dye liquor is as indicated by the broken arrows), an air line 37 extends from line 20 to a pressure-responsive element 38, which latter is in turn linked to pointer 34. Accordingly, when the cycle cam 18 opens the valve to admit air under pressure from supply line 19 to line 20, the same air pressure is applied to the element 38 and the pointer 34 moved to its full-line position. The pressure-responsive element 38 and/or the index pointer 34 is loaded, pneum-

matically or otherwise; so as to move pointer 34 to its dotted line position when the supply of air under pressure to element 38 is interrupted, as by closing the valve between pipe 19 and pipe 20. Consequently, upon each reversal of the direction of flow of the dye liquor, pointer 34 changes position and consequently changes the index datum from which differentials between it and pointer 35 are measured.

Pointer 35 is actuated from a pressure-responsive element 39, such as a diaphragm or bellows, connected through tube 40 to diaphragm 21 within the kier 1, so that pointer 35 directly reflects the actual pressure exerted at any increment of time upon diaphragm 21.

As hereinabove indicated, the cycle cam 18 also interrupts the flow of electric power to motor 4 during the period required for each re-positioning of valve 7. This is accomplished through the operation of a micro-switch 41, which controls an electric circuit energizing a holding coil in the magnetic starter 42 for motor 4.

With the parts in the positions shown in the drawings, the sequence of operations will now be described, it being assumed that the parts have just assumed the positions shown in full lines. The motor 4 begins to operate, forcing dye liquor out through valve 22, pipe 6, valve 7, pipe 8; and into kier 1 at the outside of beam 2. The dye liquor passes through the yarn on beam 2, and escapes through the hollow core of the beam to return pipe 9, from whence it passes through valve 7 to pipe 5 and pump 3, then to be recirculated. If during this period pointer 35 falls below pointer 34, pressure reducing valve 36 is automatically adjusted to increase the pressure at which air is delivered to tube 29. When the difference between pointers 34 and 35 is great enough, the pressure of the air delivered by valve 36 to tube 29 is sufficient (as for example at 9 pounds per square inch, or more) to actuate relay 27. Upon actuation of relay 27, the circuit to motor 24 is energized in a direction which causes a valve 22 to open wider, thus permitting an increased rate of flow of the dye liquor from pump 3 through the system. In the event of pointer 35 rising above pointer 34, valve 36 is actuated in the opposite direction from that indicated above, to reduce the air pressure delivered by valve 36 to tube 29 to a value below the median value (as for example to a value below 6 pounds per square inch). Consequently, under such circumstances, relay 28 is actuated to close the circuit to motor 24 for operation in the direction which reduces the orifice through valve 22 and decreases the rate of flow of dye liquor from pump 3. Such decrease in the rate of flow of dye liquor effects a reduction of the pressure within kier 1 on diaphragm 21. The reduction in pressure is reflected by a movement of pointer 35 toward the position of pointer 34, and a consequent adjustment of valve 36, so as to increase the air pressure on line 29. When the pressure on line 29 has reached the median value, relay 28 will resume its open circuit position, and further operation of motor 24 be discontinued. When the flow of dye liquor in the direction indicated by the full arrows has progressed for the desired period of time, cycle cam 18 operates to automatically interrupt the flow of power to motor 4, and concurrently interrupts the supply of air under pressure from pipe 19 to pipe 20 and cylinder 200. The interruption of the supply of air under pressure to pipe 20 causes index pointer 34 to drop to the position indicated in dotted

lines; and also causes slide valve 15 to move to the position whereat pipe 14 is connected with pipe 17, with the result that air pressure is now applied ahead of piston 11. Piston 11 then moves leftwardly, re-positioning valve 7 so as to connect pipe 5 with pipe 8, and pipe 5 with pipe 9.

Concurrently with the interruption of the supply of power to motor 4, solenoid valve 31 is de-energized so that the supply of air under pressure from pipe 30 to pipe 32 is interrupted. This immediately reduces the pressure in line 29 to below its median value, irrespective of the magnitude of the immediately preceding pressure therein. Such reduction of the pressure in line 29 actuates relay 28 which, as described above, effects a progressive reduction of the orifice through valve 22. When valve 7 has been thus re-positioned, cycle cam 18 operates to reclose the circuit to motor 4 and solenoid valve 31. Due to the re-positioning of the valve 7, the circulation of dye liquor is now in the direction indicated by the broken arrows, with the result that the exterior of the beam 2 becomes the low pressure side of the kier. During the interim in which motor 4 was not operating, the pressure on diaphragm 21 will have been gradually falling, due to continued seepage of the dye liquor through the yarn on beam 2; but when operation of motor 4 is resumed, pointer 35 may still be above the new lower position of pointer 34. In this relative position of the parts, valve 36 is in position to deliver air of lower than median pressure to line 29, with the result that relay 28 is actuated to effect operation of motor 24 in the direction which reduces the orifice through valve 22. Such operation of motor 24 continues until the pointers 34 and 35 are substantially aligned, at which time the air pressure in line 29 is at its median value, and operation of motor 24 is discontinued.

When the flow of dye liquor in the direction last described has continued for the prescribed period of time, cycle cam 18 again operates to re-position valve 7 and pointer 34. The time period of flow of dye liquor in either direction, and the number of reversals of the direction of flow during the treatment of any given beam of yarn, is a matter with which the present invention has no concern, but one which may be readily controlled in accordance with the circumstances in any particular case by appropriate adjustment of the cycle cam 18, in a manner well known to those skilled in the art.

From the foregoing description, it should be apparent that the present invention so regulates the orifice through valve 22 that when the pressure on diaphragm 21 within kier 1 is too high, valve 22 is constricted so as to reduce the rate of flow of the dye liquor. Conversely, when the pressure on diaphragm 21 is too low, valve 22 is automatically operated so as to increase the rate of flow of the dye liquor, and consequently increase the pressure on diaphragm 21. The optimum pressure on diaphragm 21 may be, for example, at about 35 pounds per square inch when the direction of flow is as indicated by the full arrows. On the other hand, when the direction of flow is reversed, the optimum pressure on diaphragm 21 will be considerably less, as for example about ten pounds per square inch. The apparatus of the present invention automatically resets itself to control variations of pressure within kier 1, irrespective of whether the optimum pressure on diaphragm 21 is a high value or a

low value at any given increment of time. Moreover, the arrangement of parts is such that upon each interruption of the flow of dye liquor, motor 24 is set into operation in a direction such as to close valve 22. Accordingly when operation of pump 3 is resumed, no sudden surge of pressure within kier 1 can occur, because valve 22 must be opened gradually.

While one complete embodiment of the invention has been described in detail, those skilled in the art will readily understand that the invention is not limited to the specific forms of control elements or operative parts as have been herein referred to, and are shown diagrammatically in the drawings. It is therefore to be distinctly understood that such modifications and variations of the apparatus disclosed as may occur to those skilled in the art, without departing from the spirit of the invention, are contemplated by and within the scope of the appended claims.

Having thus described the invention, what is claimed and desired to be secured by Letters Patent is:

1. In a dyeing apparatus comprising a kier having a beam axis port and a port leading to the exterior surface of a beam within the kier, a beam within the kier and connected with the beam axis port thereof, a pump having a discharge port and an intake port, a pipe system interconnecting the ports of the kier and the pump for conducting dye liquor from the pump to the kier and from the kier to the pump, and reversing valve means for changing the relation of connection between the pump ports and the kier ports to reverse the direction of flow of dye liquor through the kier, the combination of a power driven constrictible valve in the pipe system for regulating the rate of dye liquor flow through the kier, a pressure responsive device located within said kier, and means controlled by said pressure responsive device for actuating said valve.

2. In a dyeing apparatus comprising a kier having a beam axis port and a port leading to the exterior surface of a beam within the kier, a beam within the kier and connected with the beam axis port thereof, a pump having a discharge port and an intake port, a pipe system interconnecting the ports of the kier and the pump for conducting dye liquor from the pump to the kier and from the kier to the pump, and reversing valve means for changing the relation of connection between the pump ports and the kier ports to reverse the direction of flow of dye liquor through the kier, the combination of a power driven constrictible valve in the pipe system for regulating the rate of dye liquor flow through the kier, means controlling the operation of said valve selectively in one direction or the other pursuant to variations of the kier pressure above or below a datum, and means for automatically changing the datum in accordance with the direction of flow through the kier.

3. In a dyeing apparatus comprising a kier having a beam axis port and a port leading to the exterior surface of a beam within the kier, a beam within the kier and connected with the beam axis port thereof, a pump having a discharge port and an intake port, a pipe system interconnecting the ports of the kier and the pump for conducting dye liquor from the pump to the kier and from the kier to the pump, and reversing valve means for changing the relation of connection between the pump ports and the kier ports to reverse the direction of flow of dye

liquor through the kier, the combination of a power driven constrictible valve in the pipe system for regulating the rate of dye liquor flow through the system, means controlling the operation of said constrictible valve selectively in one direction or the other pursuant to variation of the kier pressure above or below a datum, and means for automatically changing the datum in accordance with the direction of flow through the kier, said control means being operative to move the constrictive valve toward closed position upon the interruption of flow to the kier.

4. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing valve means for changing the relation of connection between the pump ports and the kier ports to reverse the direction of flow of dye liquor through the kier, and a cycling device for periodically actuating said reversing valve means, the combination of a constrictive valve in the pipe system for regulating the rate of flow from the pump to the kier, reversible power means for operating said constrictive valve, and control means operative in accordance with the position of said pressure responsive member to energize said power means for operation in one direction or the other depending upon whether the pressure responsive member is above or below a predetermined datum.

5. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing valve means for changing the relation of connection between the pump ports and the kier ports to reverse the direction of flow of dye liquor through the kier, and a cycling device for periodically actuating said reversing valve means, the combination of a constrictive valve in the pipe system for regulating the rate of flow from the pump to the kier, reversible power means for operating said constrictive valve, and control means operative in accordance with the position of said pressure responsive member to energize said power means for operation in one direction or the other depending upon whether the pressure responsive member is above or below a predetermined datum and means responsive to operation of the cycling device for resetting said predetermined datum upon each actuation of the reversing valve means.

6. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing

ing valve means for changing the relation of connection between the pump ports and the kier ports to reverse the direction of flow of dye liquor through the kier, and a cycling device for periodically actuating said reversing valve means, the combination of a constriction valve in the pipe system for regulating the rate of flow from the pump to the kier, a reversible electric motor driving said constriction valve, electropneumatic control means for said motor arranged to close one circuit when the pneumatic pressure thereon is above a predetermined value and to close a reverse circuit when the pneumatic pressure thereon is below said predetermined value, both circuits being open when the pneumatic pressure is normal, a source supplying air at pressure substantially in excess of the aforesaid predetermined value, a reducing valve connected to receive air from said source, said reducing valve having its output port connected to said electropneumatic control means, means for automatically adjusting said reducing valve in accordance with the position of said pressure responsive member above or below a predetermined datum, and means for resetting the datum in accordance with the position of said cycling device.

7. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing valve means for changing the relation of connection between the pump ports and the kier ports to reverse the direction of flow of dye liquor through the kier, and a cycling device for periodically actuating said reversing valve means, the combination of a constriction valve in the pipe system for regulating the rate of flow from the pump to the kier, and automatic means for opening or closing the constriction valve when the kier pressure is respectively below or above a predetermined value when the cycling device is in one position and below or above a different predetermined value when the cycling device is in another position.

8. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing valve means for changing the relation of connection between the pump ports and the kier ports to reverse the direction of flow of dye liquor through the kier, and a cycling device for periodically actuating said reversing valve means, the combination of a constriction valve in the pipe system for regulating the rate of flow from the pump to the kier, a reversible electric motor driving said constriction valve, a pressure-movable device responsive to the pressure in said kier, a 70 datum device connected with said cycling device

and movable from one datum position to another as the direction of flow through said kier reverses, a differential mechanism movable in accordance with relative positions of said devices to interrupt the supply of energy to said motor when the differential between said pressure-movable and datum devices is substantially zero to energize said motor for operation in one direction when the pressure movable device is above the datum device, and in the opposite direction when the pressure movable device is below the datum device.

9. In a dyeing apparatus comprising a kier having a beam axis port and a port leading to the exterior surface of a beam within the kier, a pressure responsive member within the kier, a beam within the kier and connected with the beam axis port thereof, a pump having a discharge port and an intake port, a pipe system interconnecting the ports of the kier and the pump for conducting dye liquor from the pump to the kier and from the kier to the pump, reversing valve means for changing the relation of connection between the pump ports and the kier ports to reverse the direction of flow of dye liquor through the kier, and a cycling device for periodically actuating said reversing valve means, the combination of a constriction valve in the pipe system for regulating the rate of flow from the pump to the kier, a reversible electric motor driving said constriction valve, electro-pneumatic control means for said motor arranged to close one circuit when the pneumatic pressure thereon is above a predetermined value and to close a reverse circuit when the pneumatic pressure thereon is below said predetermined value, both circuits being open when the pneumatic pressure is at said predetermined value, a source supplying air at pressure substantially in excess of the aforesaid predetermined value, a reducing valve connected to receive air from said source, said reducing valve having its output port connected to said electro-pneumatic control means, means for automatically adjusting said reducing valve in accordance with the positions of said pressure responsive member above or below a predetermined datum, and means for resetting the datum in accordance with the position of said cycling device, an electric motor for driving said pump, and an electro-magnetic valve controlling the flow of air from said source to said reducing valve, said valve being electrically connected for energization and deenergization concurrently with said motor and arranged when deenergized to interrupt the supply of air to said reducing valve.
